United States Patent Office

Des. 180,722
Patented July 30, 1957

180,722

CHAIR

David L. Rowland, New York, N. Y.

Application April 26, 1956, Serial No. 41,214

Term of patent 14 years

(Cl. D15—1)

FIG. 1

FIG. 2

FIG. 3

Fig. 1 is a right rear perspective view from above of the chair showing my new design.

Fig. 2 is a three-quarter perspective view of the same from the front and side and from above.

Fig. 3 is a rear perspective view of the same from above.

Fig. 4 is a side perspective view thereof.

I claim:

The ornamental design for a chair, substantially as shown.
